CLAIM

The ornamental design for a swimming pool chemical dispenser or the like, as shown.

DESCRIPTION

FIG. 1 is a top plan view of a swimming pool chemical dispenser or the like showing our new design, with the cover in the fully closed position;

FIG. 2 is another top plan view thereof, showing the cover in a partially opened position;

FIG. 3 is a perspective view taken from the top and side thereof, showing the cover in the fully closed position;

FIG. 4 is another perspective view taken from the top and side thereof, showing the cover in the fully opened position; and

FIG. 5 is a bottom plan view thereof.

FIG-1

FIG-5
